(57) **CLAIM**

The ornamental design for an eyeglass display stand, as shown and described.

DESCRIPTION

The patent or application file contains at least one drawing executed in color. Copies of this patent or patent application publication with color drawing(s) will be provided by the Office upon request and payment of the necessary fee.

1. Eyeglass display stand

1.1 : Front

1.2 : Back

1.3 : Left

1.4 : Right

1.5 : Top

1.6 : Bottom

1.7 : Perspective

1.8 : Reference

1.1-1.8 are drawings showing an embodiment of the eyeglass display stand; the present product is used for displaying glasses. 1.8 is the reference reproduction, there is a drawer on the side of the display stand, and the pink marked parts with broken lines of reproduction 1.8, form no part of the claimed design.

**1 Claim, 8 Drawing Sheets
(8 of 8 Drawing Sheet(s) Filed in Color)**
